SHOWER RACK

William J. Spath, 2902 107th St., Toledo, Ohio 43611,
and Harold S. Boutin, Northwood, Ohio; said Boutin
assignor to said Spath

Filed Mar. 7, 1975, Ser. No. 556,457

Term of patent 14 years

Int. Cl. D6—01

U.S. Cl. D6—91

—FIG. 1

—FIG. 3

—FIG. 2

FIG. 6

FIG. 4

FIG. 5

FIG. 1 is a perspective view of a shower rack showing our new design;

FIG. 2 is a front elevational view thereof;

FIG. 3 is a top plan view thereof;

FIG. 4 is a side elevational view, the opposite side being a mirror image thereof;

FIG. 5 is a bottom plan view thereof; and

FIG. 6 is a rear elevational view thereof.

We claim:

The ornamental design for a shower rack, substantially as shown.
